C. D. SCHMIDT,
HOOK FOR USE WITH CHAINS,
APPLICATION FILED APR. 18, 1918.

1,339,986.

Patented May 11, 1920.

UNITED STATES PATENT OFFICE.

CHARLES D. SCHMIDT, OF WOODHAVEN, NEW YORK.

HOOK FOR USE WITH CHAINS.

1,339,986.

Specification of Letters Patent. Patented May 11, 1920.

Application filed April 18, 1918. Serial No. 229,239.

To all whom it may concern:

Be it known that I, CHARLES D. SCHMIDT, a citizen of the United States, residing at Woodhaven, Long Island, in the county of 5 Queens and State of New York, have invented certain new and useful Improvements in Hooks for Use with Chains, of which the following is a specification.

The principal object of my invention is 10 to provide a new and improved hook. One use for this hook is with non-skid chains for spoked vehicle wheels, so that such chains can be conveniently applied or removed and when applied shall be retained 15 securely in place. This and other objects of my invention will be more fully made apparent in the following specification and claims taken in connection with the accompanying drawings in which I have disclosed 20 two specific embodiments of the invention. It will be understood that modifications may be made within the scope of my invention as stated in the claims.

Referring to the drawings,

25 Figure 1 is an elevation of my improved hook in engagement with a chain link;

Fig. 2 is a side elevation of the same hook;

Fig. 3 is an end elevation looking in the 30 direction of the arrow 3 in Fig. 2;

Fig. 4 is a section taken on the line 4—4 of Fig. 2, and

Fig. 5 is an elevation of a modified form 35 in which my inventive idea may be embodied.

Referring to the modification shown in Figs. 1 to 4, the hook has an eye 11 at one end 16 adapted to be permanently engaged by the end link of a chain. Adjacent to the 40 eye 11 is a shoulder 12 with the part 13 overhanging the tip 15 of the hook. Connected with the end portion 16 is the proximal portion comprising the neck 17 and the part 21; then comes the apex 23, beyond 45 which is the distal portion comprising the parts 19, 18, and the tip 15. The projecting abutment 20 overhangs the link 24 when the hook and the link are fully assembled, the link 24 lying at this time in the notch 50 or socket 22.

Between the tip 15 and the face 13 of the shoulder 12 is the opening to receive the link in assembling the chain with the link. Extending from this opening is a reversely

curved or S-shaped passage 14 which terminates at the socket 22. 55

The abutment 20 is of considerable width as shown in Fig. 1 so that angular movement of the chain link 24 is limited relatively to the hook about an axis perpendicular to the plane of the drawing. The abutment 20 also aids materially in keeping the link 24 securely engaged by the hook. 60

The passage 14 is reversely curved as shown, in order that the link must be turned 65 through a considerable angle first one way and then the other way in order to remove it from the hook. This will be apparent from a consideration of Fig. 2. To remove the link 24 it would have to be turned clockwise to bring it to the position 24' and then counter-clockwise to remove it entirely from the tip 15 of the hook. It would be extremely unlikely that such movements could be effected accidentally so that the security 70 of engagement of the hook with the chain will be assured. It is to be noticed in this connection that the channel 14 is of approximately uniform width and only enough wider than the thickness of the 75 chain stock to provide proper clearance.

The line *a*—*b* drawn so as to touch the parts 19 and 12 of the hook lies outside the tip part 15 as shown in Fig. 2. Accordingly, the tip 15 will be protected from a 80 blow delivered by any large object, which will be received at 12 or 19 or at both points together, but not on the tip 15.

To a very great extent this will prevent the tip 15 from being bent. If a very heavy 85 blow is delivered against the part 19, or a sufficiently heavy blow by a small object against the tip 15, the only effect will be to close the passage 14 and lock the hook in engagement with the chain; evidently so 90 far as this involves any failure of the apparatus it will be on the side of safety.

Referring to the modification shown in Fig. 5, this is made of a uniform size stock steel rod bent to the shape shown in the 100 drawing. The reference characters primed have been applied in a manner to correspond to Figs. 1 to 4. The passage 14' is of substantially uniform width, enough greater than the thickness of the chain stock 105 to give a sufficient clearance. The projecting member 20' performs the same function as the like numbered element in Fig. 2 in

hindering the escape of the hook from the chain link with which it may be in engagement.

I claim:

- 5 1. A hook having a slot to receive the link of an anti-skid device to be secured, and a transversely wide projection projecting into said slot to cause said link to be at substantially right angles to the plane of the hook.
- 10 2. A hook for an anti-skid device having a base portion and a proximal portion and a tip portion extending therefrom, said tip portion being formed by reverse curves 23, 15 19, 18 and 15 connected end to end substantially in the form of an S so as to tip the link in opposite directions as it passes along said tip.
- 15 3. A hook adapted to coöperate with the links of an anti-skid device for vehicle wheels, comprising a base portion and a tip portion extending therefrom, and providing reversely curved surfaces spaced relatively to the link surfaces to tip said link first 20 in one direction and then in another as said link passes along said tip portion.
- 25 4. A hook adapted to coöperate with the links of an anti-skid device for vehicle wheels, comprising a base and a proximal portion and a tip portion extending therefrom, said tip portion being formed by reverse curves connected end to end substantially in the form of an S and being of only 30 slightly less thickness than the width of the 35 opening in said link.
5. A hook adapted to coöperate with the links of an anti-skid device for vehicle wheels, comprising a base and a proximal portion and a tip portion extending therefrom, said tip portion being formed by 40 reverse curves connected end to end substantially in the form of an S and being spaced from said base and proximal portions by a reversely curved slot.
6. A hook having a base and a curved 45 portion with parts proximal to and distal from said base, an abutment projecting across from the proximal part toward the distal part said hook being adapted to coöperate with a link engaged thereby and of 50 stock substantially filling the space between said abutment and the apex, said abutment being transversely wider than the apex part of the hook.
7. A hook having a base and a curved 55 portion with parts proximal to and distal from said base, the distal part being curved relatively to the proximal part so as to be convex toward the proximal part and an abutment projecting across from the proximal part toward the distal part near the apex so as to form a reversely curved passage between the proximal part and the said abutment on one side and the distal part on the other side said hook being adapted to coöperate with a chain of links each having an opening slightly greater than the thickness of the distal part of the hook. 60 65

CHARLES D. SCHMIDT.
